SLOPER MECHANISM FOR EXCAVATING MACHINES

Henry L. Meyer, Cleveland Heights, and Andrew J. Di Liddo, Cleveland, Ohio, assignors to The Cleveland Trencher Company, Cleveland, Ohio, a corporation of Ohio

Filed Aug. 12, 1957, Ser. No. 677,691

8 Claims. (Cl. 37—97)

This invention relates to an excavating machine for digging trenches and more particularly to the mechanism used to slope the sides of the trench.

It is often-times desirable in the digging of trenches or ditches to slope the sides of the trench so that they diverge outwardly with respect to one another. The latter is particularly true when digging a system of ditches for irrigation or like purposes. Various mechanisms have been devised in the past to slope the sides of a trench. However, these prior art arrangements generally leave much to be desired in that they are either extremely complex, resulting in a machine of undesirable weight and cost, or they do not satisfactorily and effectively bevel the sides of the trench. In this connection, many of the prior art sloper mechanisms have not extended all the way to the bottom of the trench, but have been terminated short thereof due to the problem of providing an adequate support on the machine for the lower extremity of the sloper mechanism, and thus the walls of the trench have not been evenly sloped throughout their total extent.

The present invention provides a trenching machine embodying a cutting blade mechanism which effectively and efficiently slopes the sides of the trench and which extends all the way to the bottom of the trench to provide an evenly and cleanly cut, sloped excavation. Moreover, the present invention provides a trenching machine of the above type having sloper mechanism which is adjustable in a transverse direction to thereby provide means for changing the degree of slope of the sides of the excavation. The bottom support for the sloper mechanism of the instant invention extends from inside the excavating wheel and laterally to either side thereof, and embodies an auxiliary cutting blade structure for loosening material to be sloped adjacent the sides of the excavating unit of the machine. The bottom support is so positioned on the machine so that it is disposed comparatively close to the lower ends of the generally upright cutting blade elements of the sloper mechanism and yet so arranged that there is no interference with the material to be sloped.

In a modified form of the invention a plurality of sloper blades are provided on both sides of the machine, primarily for use in heavier soils where one set of blades cannot readily be pulled through the soil to cut a wide trench. A novel arrangement for pivotally mounting certain of the blades of the modified mechanism on the machine is provided to permit raising and lowering of the excavating unit.

Accordingly, the primary object of the invention is to provide an excavating machine having an excavating unit and embodying a cutter blade sloper mechanism disposed on either side of the excavating unit for efficiently and effectively sloping the sides of the resultant trench throughout substantially the total vertical extent thereof.

Another object of the invention is to provide an excavating machine of the latter described type embodying means for adjusting the angular position of the sloper

mechanism with respect to the horizontal and in a transverse direction, to thereby furnish means for readily changing the degree of slope of the sides of the excavated trench.

5 A further object is to provide an excavating machine of the latter described type having a generally upright extending cutter blade mechanism disposed adjacent the sides of the excavating unit of the machine for sloping the sides of the resultant excavation, and wherein the 10 bottom support structure for the cutter blade mechanism extends through the excavating unit laterally of the side extremities thereof and includes an auxiliary cutting blade mechanism for loosening the soil to be sloped adjacent the sides of the excavating unit.

15 A still further object of the invention is to provide an excavating machine having a plurality of generally upstanding, cutter blade sloper mechanisms disposed adjacent the sides of the excavating unit and disposed in generally echelon relationship and wherein at least one 20 of said mechanisms is pivotally mounted on the machine to permit rotational movement thereof relative to the machine.

25 Other features and advantages of the invention will be apparent from the following description taken in conjunction with the accompanying drawings wherein:

Fig. 1 is a side elevational view of an excavating machine embodying the invention;

Fig. 2 is a rear end elevational view of the machine of Fig. 1 with a portion of the crumbing structure of the 30 machine cut away to better illustrate the cutter blade sloper mechanism and attaching structure therefor;

Fig. 3 is an enlarged vertical sectional view taken generally along line 3—3 of Fig. 1 looking in the direction of the arrows and illustrating in greater detail the mounting structure for the sloper blade mechanism of the invention;

Fig. 4 is an enlarged vertical sectional view taken generally along line 4—4 of Fig. 3 looking in the direction of the arrows and illustrating the construction of the lower supporting structure for the sloper mechanism and the associated auxiliary cutter blade for loosening the soil to be sloped adjacent the sides of the excavating unit of the machine;

Fig. 5 is an enlarged fragmentary top view taken generally along line 5—5 of Fig. 2 showing the bracket arrangement for connecting the sloper blade mechanism to the upper support structure for such mechanism;

Fig. 6 is an enlarged fragmentary rear end elevational view illustrating one arrangement of ground engaging support shoe adapted for attachment to the upper support structure of the sloper mechanism for supporting the digging unit and associated sloper mechanisms at a predetermined depth of excavation;

Fig. 7 is a fragmentary side elevational view of a modification of the invention illustrating the use of a plurality of sloper mechanisms mounted on a side of the excavating machine adjacent the excavating unit and adapted primarily for use in heavier soils where one set of blades cannot readily be pulled through the soil to cut a sufficiently wide trench;

Fig. 8 is a diagrammatic rear end elevational view illustrating the generally echelon relationship between the sloper blade mechanisms of the modified form of the invention;

Fig. 9 is an enlarged fragmentary sectional view of the upper support structure for one of the cutter blades of the modified sloper mechanism taken generally along line 9—9 of Fig. 7 and illustrating in detail the arrangement for pivotally mounting the sloper blade on the support structure;

Fig. 10 is an enlarged, fragmentary, rear end elevational view taken generally along line 10—10 of Fig. 7

and illustrating a rigid connection between the lower support for the sloper mechanism and the generally upright blade elements of the latter mechanism.

In the drawings, the invention is illustrated as being applied to a crawler propelled excavating machine. The machine illustrated is of the general type shown and described in U.S. Patent No. 2,280,004, issued April 14, 1942, to Vincent S. Penote, et al., and accordingly will not be described in detail here. However, such an excavating machine broadly includes a base supporting frame 2, supported on suitable tractor treads 3, a motor 4 mounted on the forward end of the machine, mast structure 5 for supporting thereon vertically movable boom structure 6, an excavating wheel or unit 7 rotatably mounted on boom 6 by means of frame and wheel arrangement 8 and 8a, and a transversely extending discharge conveyor 9 which is drivingly connected to the motor unit 4 of the machine by a drive-assembly arrangement generally indicated by reference number 10. Boom structure 6 and associated excavating wheel 7 may be raised and lowered by means of cable and pulley system 12 actuated by winding drums 14 and 15 mounted on the machine frame.

Referring in particular to the embodiment of the invention illustrated in Figs. 1 to 6 inclusive of the drawings, reference number 20 designates generally the sloper mechanism for beveling the sides of the trench dug by the digging wheel 7 of the machine.

In the embodiment shown, the upper support 22 (Fig. 3) for sloper mechanism 20 comprises a centrally disposed housing portion 24 extending transversely through the digging wheel 7 and attached by any suitable means such as welding, etc. to the longitudinally extending beam elements 6a of boom structure 6. Housing 24 is of preferably hollow, fabricated construction and receives in telescoping relationship therewith, outer support arms 26. Arms 26 may be of any suitable construction, preferably conforming to that of housing portion 24, and include a series of spaced openings 26a therein. Housing portion 24 also comprises openings 28 adjacent the outer ends thereof for aligned relationship with one of the respective openings 26a in the corresponding one of support arm members 26. A retaining member 30, such as a bolt or headed pin, extends through openings 28 and 26a and maintains the arm elements in attached assembled relationship with housing 24.

A bracket member 32 (Figs. 3 and 5) is pivotally mounted on the outer end of each of arm elements 26 as by means of pin 34. Bracket member 32 comprises side and end walls 34a and 34b and is open at the top and bottom thereof to define a passageway 35 for receiving in supporting, sliding relationship a cutter blade element 36. Lugs 37 extend inwardly from the inner of side walls 34a of the bracket and are disposed in confronting relationship with the outer ends of arm element 26. The aforementioned pin or bolt 34 maintains bracket member 32 in assembled relationship with the upper support structure 22 and provides for pivotal movement of the bracket in a generally vertical plane about the outer end of arm element 26 of the support structure. Bracket members 32 are disposed at an angle with respect to the longitudinal vertical plane of the outer end of the associated arm element 26 or of the corresponding center plane of the excavating machine and diverge outwardly in a forward direction with respect thereto as can be best seen from Fig. 5 of the drawings.

In the embodiment shown the bottom support 39 for the sloper mechanism 20 comprises an elongated bar-like structure (Figs. 3 and 4) preferably of fabricated construction and includes a bottom element 40 of generally V or angle shape in vertical cross-section, a top element 42 of generally inverted V or angle shape in vertical cross-section, and an intermediate auxiliary blade member 44 attached to elements 40 and 42 as by means of welds. An elongated strengthening bar 46 is attached

4
to top element 42 adjacent the sides of excavating unit supporting frame structure 8 and is connected to the latter as at 47 to reinforce the bottom support structure 39. Top element 42 of support structure 39 could also be so arranged as to be connected to frame structure 8 of the excavating wheel unit 7, as by means of welds, to positively fasten bottom support structure 39 to the machine.

Blade 44 has its front edge sharpened or beveled as at 48 on its laterally extending portions and is adapted to loosen certain of the material to be sloped by the generally upright sloper blades 36. Blade 44 is preferably disposed so as to slope generally downwardly in a forward direction, as best shown in Fig. 4, so that the dirt being cut by blade 44 tends to hold or draw the latter into cutting contact therewith. The bottom element 40 of support structure 39 causes the material being cut by blade 44 to flow away from the underside of the blade and thus further loosens the material being sloped by main cutting blades 36. It will be seen from Fig. 3 that the outer ends of blade 44 extend substantially to the inner sides of sloper blades 36, but do not interfere with material to be sloped by blades 36 or with the structure of the sloper blades.

The outer ends of bottom support structure 39 are each connected by means of a hinge bracket 50 to lower portions of the associated one of main sloper blade members 36. Bracket 50, in the embodiment shown, comprises a plate element 52 secured to the inner side of blade 36 and inwardly extending lug portions 53 hinged as by means of pin or bolt 54 to lower support structure 39.

Main cutter blade members 36 comprise elongated generally upstanding bar or plate-like elements which, as aforesaid, are rigidly connected to bottom hinge bracket 50 adjacent the lower extremity of the blades, and which extend upwardly through passageway 35 in the corresponding one of the upper hinge bracket members 32. Blades 36 diverge upwardly with respect to one another and slope diagonally outwardly with respect to the longitudinal vertical center plane of the excavating machine. The front cutting surface of the blade is beveled or cut inwardly in a transverse direction as at 56, Figs. 1 and 5, which in combination with the outward divergence in a forward direction of the blade with respect to the longitudinal vertical center plane of the machine, acts to move the material being beveled from the sides of the trench into the path of travel of the main excavating wheel, from which it is carried by the bucket portions 57 thereof to the discharge conveyor 9 to be deposited on either side of the excavating machine. Blades 36 extend generally to the horizontal plane of the lower extremity of the excavating wheel 7, and thus bevel the sides of the trench throughout their full vertical extent. It will be understood that the aforementioned bottom support structure 39 which includes auxiliary cutting blade 44 makes it possible to extend the main sloper blades 36 all the way to the bottom of the trench being dug by the excavating unit 7, thus providing with only one pass of the machine, an excavation having evenly and completely tapered sides. Blades 36 preferably slope diagonally rearwardly in an upward direction as best seen in Fig. 1 so that the material being sloped tends to pull or hold the blades in cutting contact with the ground.

65 The angle at which the sloper blades 36 diverge upwardly with respect to one another, may be readily changed by merely removing connecting means 30 from the housing and arm structure 24 and 26, sliding arm elements 26 inwardly or outwardly with respect to housing portion 24 until another of openings 26a in arm elements 26 become aligned with openings 28 in the associated end of housing portion 24, and then reinserting the holding pin 30 through the aligned openings. Thus a wide range of degrees of slope may be provided for the excavation and one side of the latter may be sloped at

a different angle as compared to the other side thereof. As the angular relationship of the blades is changed, the latter will, of course, pivot about their connections 54 to the bottom support structure 39 and will slide in unrestricted relationship in passageway 35 of the associated bracket housing 32 of upper support structure 22. Blades 36 extend upwardly beyond brackets 32 a sufficient amount to insure that the blades 36 will be retained in assembled relationship with the brackets 32 irrespective of the telescoping adjustment of the supporting arms 26 of the upper support structure.

A crumbing shoe 60 extends downwardly from the rearward end of boom structure 6 of the machine and is adapted to engage the floor of the excavation and to push or propel any loose material in the excavation forward so that it may be picked up by the buckets of the excavating wheel 7, thereby maintaining the floor of the excavation or trench comparatively clean. Crumbing shoe 60 includes lateral side panels 62, each of which has an outer edge configuration generally similar to the slope of the contoured sides of the excavation. In the embodiment shown, the crumbing shoe is so constructed to conform to an angular relationship of the blades of approximately 45° with respect to the horizontal. If the divergent position of the blades with respect to one another is adjusted in accordance with the aforescribed teachings, the crumbing shoe will, of course, have to be removed from the machine or will have to be replaced by a crumbing shoe having lateral side panels conforming to the adjusted slope of the sides of the trench.

In Fig. 6, there is shown a ground-engaging support shoe device 65 which may be attached to each outer end of upper support structure 22 of the sloper mechanism for supporting the digging unit and associated sloper mechanism at a predetermined depth of excavation. Device 65 is adapted primarily for use on a machine operating over comparatively level ground. Device 65 comprises a base portion 66 adapted to be attached by any suitable means such as bolts 67 to an outer end of one of the arm elements 26 of the upper support structure 22, a laterally extending beam or cantilever portion 68 and a generally vertically disposed collar portion 70. Collar portion 70 has a series of generally vertically spaced openings 72, extending generally horizontally therethrough and is adapted to receive therein depending leg element 74. Leg element 74 is vertically movable relative to collar 70 and has generally horizontally disposed openings 76 extending therethrough adapted to be aligned with openings 72 in collar 70 and to receive retaining members, such as bolts 78 for holding the leg and collar element in predetermined assembled relationship. A ground-engaging shoe skid 80 is secured to the lower end of a leg element 74. Skid 80 is of generally arcuate configuration in side elevation and is adapted to slide along the ground as the excavating machine progresses forwardly to support the digging wheel and associated sloper mechanism at a predetermined depth of excavation. Holding means 78 may be removed and the leg 74 and associated skid 80 readily adjusted upwardly or downwardly for various depths of excavation. It will be apparent that the ground in the vicinity of the excavation must be of a comparatively level nature in order to utilize shoe support device 65.

Referring to Figs. 7 to 10 inclusive, there is shown a modification of the invention comprising in general a plurality of sloper blade mechanisms mounted on each side of the excavating unit. The modified form of the invention is particularly adapted for use in heavier types of soils, where one set of blades cannot readily be pulled through the soil to cut a sufficiently sloped trench. The rearward one 84 of the sloper mechanisms may be generally similar to the first described form of the invention; the forward one of the sloper mechanisms could also be generally similar in construction to the first described embodiment of the invention except that the length of the

generally upright blades thereof would have to be so shortened so as not to extend past the path of travel of the buckets 57 of the excavating wheel, in order to enable the forward blades to be able to effectively bevel the sides of the trench and direct the cut material into the path of travel of the buckets 57, as will be clearly understood by those skilled in the art. A transversely extending bottom support structure, similar to the bottom support 39 of the rearward sloper mechanism could be provided extending through the wheel 7 and suitably attached to frame members 8 in a manner similar to that utilized for aforescribed bottom support 39.

However, in the embodiment shown, in Figs. 7-10, the excavating machine is particularly adapted for use in sloping the sides of a trench which has already been cut by a conventional trenching machine. The machine illustrated in Figs. 7-10 straddles the pilot trench and in one pass completes the sloping of the sides thereof. It will be understood by those skilled in the art that the double sloper mechanism illustrated in Fig. 7 could not be effectively used without first digging a pilot trench since the forward blades and bottom support structure therefor, as shown, extend past the path of travel of the buckets 57 of the excavating wheel. The forward one 86 of the sloper mechanisms illustrated in Figs. 7-10 is mounted on supplementary frame structure 88, attached to the underside of boom 6. Referring to Fig. 9, the upper support structure 89 for forward sloper mechanism 86 comprises a housing portion 90 generally cylindrical-like, in vertical cross section interior configuration, and having an inner abutment portion or shoulders 90a disposed generally adjacent the outer ends of the housing. A support arm 92 extends in telescoping relationship into each end of housing portion 90 and includes an abutment portion 92a on its inner end which preferably corresponds in peripheral contour to the inner configuration of housing 90. Portion 92a is adapted to engage abutment shoulders 90a in housing 90 to maintain support arm 92 in assembled relationship with housing 90 when arms 92 are in their maximum extended positions. Each of arms 92 comprises a series of laterally spaced openings 94 therein. A collar 96 encircles each of arms 92 adjacent its associated outer end of housing 90 and has an opening 96a therein for receiving a holding element 98 such as a bolt or pin which extends through the aligned openings in arm 92 and collar 96 for retaining the collar secured to the arm element. Collar 96 on its inner end has flange portion 99 which is received in a threaded cap 100 which, in turn, is removably attached or threaded to threaded end portion 101 of housing 90. A support bracket 102 generally similar to the corresponding bracket 32 of the first described embodiment of the invention is pivotally mounted on the outer ends of each of arms 96 for receiving and supporting forward blade 104 of the sloper mechanism. Blade 104 may be secured to bracket 102 by any suitable means.

The angular position of blade 104 with respect to the horizontal can be changed by removing holding element 98 and aligning one of the other openings 94 in arm 92 with opening 96a in collar 96, and then reinserting element 98. Arm 92 and attached collar 96 is rotatable with respect to cap 100 and associated housing 90 for a purpose to be hereinafter described.

As aforesaid the bottom support structure for the forward sloper mechanism 86 of the modification may be generally similar to the hinged connection, bottom support of the first described embodiment of the invention, except that it is flexibly connected to the machine chassis instead of being rigidly attached to the excavating unit structure, as will hereinafter be more thoroughly discussed. However, if the feature of providing for transverse adjustment of the divergence of the generally upright sloper blades 36, 104 with respect to one another and to the longitudinal vertical center plane of the

machine is not desired, the connection between the laterally extending supporting portions of the sloper mechanisms and the generally upright sloper blades could be a substantially rigid connection in a transverse direction, rather than the hinged connections heretofore illustrated. In the latter instance the bottom support structure 106 (Figs. 7 and 10) comprises an auxiliary cutting blade 108 which extends transversely of the machine chassis, forwardly of the path of travel of buckets 57 of the excavating wheel 7. The outer ends of the blade 108, in the non-hinged connection illustrated, are rigidly connected to plate elements 109 which are secured to the associated one of the generally upright blade members 104. Auxiliary blade 108 extends substantially all the way to the inner surfaces of blades 104 and thus loosens the soil to be sloped by blades 104, but does not interfere with the material being sloped by the upright sloper mechanism. An inverted V-shaped member or strengthening angle 110 is secured to the upper surface of blade 108 by any suitable means and is terminated short of the outer ends of blade 108. A bracket 112 is attached to each outer end of member 110 and a flexible member 114, such as a cable, is attached at one end to bracket 112 and at the other end is secured to the chassis of the excavating machine at the generally forward end of the machine chassis. A turn-buckle 118 is provided for changing the effective length of the cable 114. Cable 114 extends upwardly through the previously dug pilot trench and therefore there is no interference between the cables and the defining walls of the trench. Thus it will be seen that the forward sloper blades 104 are prevented from pivoting in a counter-clockwise direction (as viewed in Fig. 7) during sloping operations by cable 114 while they may be pivoted in a clockwise direction about housing 90 of upper structure 89. If boom 6 and associated digging unit 7 are angled vertically about the axis of rotation of digging wheel 7, upon proper actuating of the winding drum and cable system 12, the swinging connection of the lower support structure 106 to the machine chassis and the pivotal connection of the upper support structure 89 to housing 90 will permit such vertical angling without distortion or strain of the lower connection between the sloper mechanism 86 and the machine chassis. The flexible cable 114 also conveniently provides for vertical movement of the boom structure 6 and associated excavating wheel 7 with respect to the mast structure on the machine chassis.

Referring to Fig. 8, it has been found that the most desirable angular relationship so far as cutting operations are concerned, between the dual sloper mechanisms is as shown, the generally upright blades 36 of the rearward sloper mechanism 84 being disposed at an angle of approximately 45° with respect to the horizontal, while the generally upright blades 104 of the forward sloper mechanism 86 being disposed at an angle of approximately 60° with respect to the horizontal.

With the pivotal mounting and flexible bottom connection of the forward sloper mechanism 86, it will be seen that the latter may be readily pivoted upwardly out of biting engagement with the sides of the excavation and thus utilize only the rearward set of sloper blades to slope the sides of the trench, when such an arrangement is deemed desirable.

From the foregoing description and accompanying drawings, it will be understood that the invention provides an excavating machine having a novel arrangement of sloper mechanism for sloping the sides of the trench dug by the digger unit of the machine and wherein the sloper mechanism extends all the way to the bottom of the excavation to thereby effectively slope the side walls of the trench throughout their full vertical extent. The invention also provides a sloper mechanism which is adjustable in a transverse or lateral direction to thereby provide means for varying the degree of slope of one or both sides of the trench. Moreover, the invention

provides a dual arrangement of sloper mechanisms primarily for use in heavier soils and wherein at least one of the sloper mechanisms may be mounted for pivotal movement in a generally longitudinal plane and wherein a novel arrangement is provided for connecting the mechanism to the machine chassis.

The terms and expressions which have been employed are used as terms of description and not of limitation and there is no intention in the use of such terms and expressions of excluding any equivalents of the features shown and described or portions thereof, but it is recognized that various modifications are possible within the scope of the invention claimed.

We claim:

1. In an excavating machine including a frame and an excavating unit carried by the frame for digging a trench-like excavation, cutter mechanism mounted adjacent the sides of said unit for sloping the walls of the excavation coincident with the digging thereof, said cutter mechanism comprising a plurality of generally upright blade elements extending substantially to the bottom of said excavation and means extending transversely with respect to said machine for mounting said blade elements thereon, said means comprising generally vertically spaced bar-like elements, extending through said unit and being connected at their outer ends to said blade elements, a ground engaging shoe device mounted adjacent each outer end of the uppermost of said bar-like elements, said shoe device comprising a base portion for attachment to said last mentioned bar-like element and an arm portion extending laterally outwardly from said last mentioned element, a leg portion connected to said arm portion and extending downwardly therefrom, and a shoe portion secured to the lowermost end of said leg portion and adapted to slidably engage the ground upon movement of said machine, said device being adapted to support said unit and associated cutter mechanism at a predetermined depth of excavation.
2. In an excavating machine including a frame and a wheel excavating unit carried by the frame on the rearward end thereof, sloper mechanism mounted adjacent the sides of said unit for sloping the sides of an associated preformed trench, said mechanism comprising at least one pair of generally upright, when in normal operative position, longitudinally spaced blade elements disposed adjacent each side of said unit and mounted in generally stationary relation with respect to said frame during the sloping operation, respective ones of said blade elements on opposite sides of said unit diverging upwardly with respect to one another, the rearwardmost set of said respective blade elements having a greater angle of divergence with respect to one another than the adjacent set of said blade elements, support means extending transversely of said unit and attached to said blade elements for mounting the latter on said machine, said support means comprising generally vertically spaced elongated bar-like structure, the lowermost of said support structure for each set of said upright blade elements including a cutter blade element extending transversely with respect to said frame and laterally of said excavating unit substantially to a juncture with the associated of said upright blade elements, the uppermost of said support structure for said adjacent set of blade elements being rotatable with respect to the machine whereby said adjacent set of blade elements may be pivoted out of cutting position with respect to the sides of the trench, the lowermost of said support structure of said adjacent set of blade elements being disposed generally forwardly of the rotary path of travel of said unit, flexible means connected at one end to said last mentioned support structure and at the other end to said frame of said machine for maintaining said pivotally mounted set of blade elements in predetermined longitudinally spaced relation with respect to the other set of blade elements during sloping operations of said machine and for providing

means for pivoting said adjacent set of blade elements out of said normal operative position whereby said unit and said other set of blade elements may be utilized in excavating operations.

3. In a mobile trench excavating machine including a main frame, a generally longitudinally extending boom carried by said frame and extending from the rearward end thereof, said boom being mounted with respect to said frame for movement in a generally vertical plane, a bucket equipped rotary wheel type excavating unit carried by said boom for digging movement in a generally vertical plane, said wheel excavating unit being adapted to produce a trench having generally vertical side walls, sloper mechanism mounted adjacent the sides of said wheel excavating unit for beveling the walls of the trench coincident with the digging thereof, said sloper mechanism comprising a pair of generally upright cutting blade elements disposed on opposite sides of said wheel excavating unit and diverging with respect to one another in an upward direction, each of said blade elements commencing substantially at a horizontal plane passing through the lowermost extremity of said wheel excavating unit and extending upwardly to at least the general level of said boom, and means for supporting said blade elements in stationary relation with respect to said machine during excavating operations, said means comprising an upper support extending transversely through said wheel excavating unit and laterally of either side thereof and a lower support extending transversely through said wheel excavating unit and laterally of either side thereof, said upper support being supported by said boom and being disposed generally rearwardly of said lower support, said lower support being supported by said boom in fixed relation therewith and being disposed adjacent the lowermost portion of said wheel excavating unit, said lower support including auxiliary cutting blade portions disposed in a generally horizontal plane and extending transversely between said generally upright blade elements and said wheel excavating unit for loosening the soil intermediate the sides of said wheel excavating unit and said upright blade elements and at said lower support during excavating and sloping operations.

4. In a mobile trench excavating machine in accordance with claim 3 wherein said sloper mechanism includes means for adjusting the amount of divergence of said generally upright blade elements with respect to one another to thereby provide for changing of the degree of sloping of the sides of a trench.

5. In a mobile trench excavating machine in accordance with claim 3 wherein said generally upright blade elements diverge outwardly with respect to one another in a forward direction and with respect to the longitudinal vertical center plane of said wheel excavating unit whereby said last mentioned blade elements tend to move the material bevelled from the sides of the trench during excavating operations into the path of travel of said wheel excavating unit.

6. In a sloper mechanism adapted for attachment adjacent a rotary wheel type excavating unit of a digging machine for sloping the sides of a trench dug by said unit coincident with the digging of the trench, said mechanism comprising at least one generally upright relatively stationary cutter blade element adapted for disposal adjacent each side of said excavating unit, said blade elements on opposite sides of said unit diverging upwardly with respect to one another and adapted to commence substantially at the bottom extremity of said unit, and generally vertically spaced support means adapted to extend transversely through and laterally of the sides of said unit and be supported in generally stationary relation with respect to said machine, said support means being connected at their outer ends to said blade elements for supporting the latter in stationary relation with respect to said machine during digging operations, the uppermost of said support means including bracket members pivotally mounted adjacent each outer end thereof, each of said bracket members comprising front, rear and side walls defining therebetween a generally upright extending passageway for receiving therethrough in comparatively loose relationship the respective one of said upright blade elements and the lowermost of said support means adapted to be positioned adjacent the bottom portion of said unit and including auxiliary cutter blade portions disposed in a substantially horizontal plane for loosening the soil at said lowermost support means and intermediate said upright blade elements and the sides of the unit during digging operations, said support means including means for adjusting the amount of divergence of said upright blade elements with respect to one another.
7. In an excavating machine in accordance with claim 1, wherein said leg portion is adjustable vertically with respect to said arm portion for varying the depth of excavation.
8. In a sloper mechanism in accordance with claim 6, wherein said bracket members extend diagonally outwardly in a forward direction with respect to the longitudinal vertical center plane of the digging machine.
